Primary Examiner — Garth Rademaker*Assistant Examiner* — Katie Stofko Mroczka(74) *Attorney, Agent, or Firm* — Peter J. Ims; Westman, Champkin & Koehler, P.A.(57) **CLAIM**

The ornamental design for a pet treat, as shown and described.

DESCRIPTION

FIG. 1 is a perspective view of a pet treat;

FIG. 2 is a top view thereof, where the top view is symmetric with the bottom view; and,

FIG. 3 is a side view thereof, where the right side is symmetric with the left side.

The broken lines shown in FIG. 1 illustrate portions of the pet treat that form no part of the claimed design.
